SPRAY NOZZLE

Sidney D. Lapham, Martinez, Calif., assignor to
 Shell Development Company, San Francisco,
 Calif., a corporation of Delaware

Application April 19, 1944, Serial No. 532,005

4 Claims. (Cl. 299—63)

The present invention relates to spray nozzles and more particularly to spray nozzles adapted for treating the interior of containers and the like.

There are numerous industrial and other applications for spray nozzles which may be inserted in the openings of containers and serve to coat the interior surfaces of or otherwise treat the interiors of the containers. Specific examples of such applications coming under consideration are the cleaning and coating of drums, barrels, cans, bottles etc. In cleaning and/or coating such containers, the greatest difficulty lies in providing complete and uniform wetting of the interior surfaces with the material which is being sprayed. During cleaning operations, a spray nozzle is normally employed which provides an impingement jet, the stream of cleaning fluid serving as a mechanical force, in addition to the solvent action, to assist in removing undesirable deposits from the interior of the container. When removing heavy deposits such as asphalt, gums, resins and the like, it is particularly important that complete coverage of the interior of the container by the impinging stream is attained, otherwise the cleaning process is either ineffective or unduly time consuming. In coating the interiors of containers, an atomizing nozzle is generally employed which develops a relatively fine spray. In such instances it is also imperative that the atomizing nozzle provide complete and uniform coverage of the interior of the container to avoid uneven coatings which tend to flow or wrinkle.

It is an object of the present invention to provide an improved spray and atomizing nozzle adapted to treat the interior surfaces of containers. A further object is to provide a nozzle of this type which will effectively and completely cover the interior surfaces of containers in a minimum period of time. Another object is to provide a spray nozzle which will provide complete impingement coverage of the interior of a container or the like. Still another object is to provide an atomizing nozzle which will evenly coat the interior surfaces of a container. Other objects, together with some of the advantages to be derived in utilizing the present invention, will become apparent from the following detailed description thereof, taken together with the accompanying drawing illustrating a sectional elevation of a nozzle arrangement according to the invention.

In the drawing, a housing 10 in cylindrical form is fixed to or formed as a part of base

member 1. Liquid conduit 2 is provided with liquid inlet port 21 and is enclosed within housing 10, being rigidly attached to base 1 and defining an annular air chamber 22 between housing 10 and conduit 2. An air inlet port 40 serves to admit air to annular chamber 22. Conduit 2 extends through the upper end of housing 10 and terminates within nozzle drive housing 7. Sleeve 8 is rigidly attached to nozzle drive housing 7 and extends downwardly therefrom enclosing a section of conduit 2 and defining an annular chamber therebetween which is in direct flow communication with annular air chamber 22. Sleeve 4 encloses a section of housing 10 and is connected to sleeve 8 through bearing housing 9 which is rigidly attached to sleeve 8. The lower portion of sleeve 4 is adapted to receive annular packing 5 and threaded bushing 3 which serves to secure packing 5. The upper end of sleeve 4 is threaded to engage bearing housing 9 which is supported by bearing 11 which is mounted in housing 10 near the upper end thereof.

Lubrication fitting 36 permits introduction of lubricant between sleeve 4 and housing 10, sleeve 25 4 being rotatable with respect to housing 10, and also to lubricate bearing 11. Ring gear 18 is rigidly mounted on sleeve 4, being driven by any suitable gear means engaging gear teeth 6.

Conduit 2 terminates inside nozzle drive housing 7, bevel gear 15 being rigidly mounted on the discharge end of conduit 2. An annular packing 12 is provided between conduit 2 and nozzle drive housing 7, bushing 13 securing packing 12 in place. A second bevel gear 20 is rotatably mounted in nozzle drive housing 7, preferably at a right angle to bevel gear 15, and meshes therewith. Nozzle housing 19 is rigidly attached to the external projection of bevel gear 20 and rotates with bevel gear 20.

40 An L-conduit 17 extends downwardly through bevel gear 15 and terminates within conduit 2, being rotatable with respect to both of these elements, and also extends through bevel gear 20, terminating in flow communication with conduit 45 23 in nozzle housing 19. Bevel gear 20 is free to rotate with respect to that portion of L-conduit 17 passing therethrough.

Conduit 23 is provided in nozzle drive housing 7 in flow communication with annular air chamber 22 at one end and with an annular air manifold 24, also provided in nozzle drive housing 7, at the other end. Annular packings 31 and 32 are provided on each side of air manifold 24 and are retained by nozzle housing 19 which is rotatable with respect thereto.

Nozzle housing 19 is threaded to receive spray nozzle 27, preferably perpendicular to the axis of rotation of nozzle housing 19, and atomizing tip 35. Spray nozzle 27 is provided with perforations at 14 in flow communication with conduit 29. Atomizing tip 35 is in flow communication with air manifold 24 through conduit 25 in nozzle housing 19. Clean-out plugs are provided in the base of spray nozzle 27 at 33 and in nozzle housing 19 at 34.

A ball-check lubrication fitting is provided in the top of nozzle drive housing 7 at 16. Lubricant introduced at 16 serves to lubricate bevel gears 15 and 20 as well as the bearing surfaces between bevel gear 20 and nozzle drive housing 7, between L-conduit 17 and bevel gear 20, and between L-conduit 17 and conduit 2.

The operation of the nozzle, when used for atomizing purposes, is as follows: the liquid which is to be atomized is supplied under pressure to conduit 2, passing upwardly through conduit 17, through conduit 29 and thence into spray nozzle 27 through perforation 14. Air or other suitable atomizing gas is supplied under pressure through air inlet port 40 from whence it passes through annular air chamber 22 into conduit 23 and air manifold 24. Conduit 25 receives air from air manifold 24 and delivers the same through annular space 26 between atomizing tip 35 and spray nozzle 27.

Ring gear 18 is rotated by any suitable means, resulting in rotation of sleeve 4, bearing housing 9, sleeve 8 and nozzle drive housing 7. Since conduit 2 retains bevel gear 15 in a stationary position, it will be seen that the rotation of nozzle drive housing 7 carrying bevel gear 20 results in rotation of bevel gear 20 as well as rotation of L-conduit 17 within conduit 2.

Rotation of bevel gear 20 results in corresponding rotation of nozzle housing 19 carrying spray nozzle 27 and atomizing tip 35. Bevel gears 15 and 20 are provided with unequal numbers of teeth, one of these gears preferably having one tooth less than the other. Thus, for example, if gear 15 is provided with 24 teeth and gear 20 with 23 teeth, one complete rotation of nozzle drive housing 7 will bring about 1 and $1/23$ rotations of gear 20 and spray nozzle 27 attached thereto. In order to return nozzle drive housing 7 and spray nozzle 27 to the same relative starting positions, it is necessary to rotate nozzle drive housing 7 a total of 23 times, resulting in 24 rotations of spray nozzle 27. In practical operation, when the nozzle head is inserted in a drum or the like, it will be seen that the stream from the spray nozzle will trace 24 different path units on the interior of the drum before the cycle is completed and the first path unit is again traced. The greatest number of different unit paths are always attained when the number of teeth on gears 15 and 20 are prime with respect to each other. For example, in the instance cited above, 24 different unit paths are traced by the nozzle stream if either of the gears has 24 teeth and the other has 23, 19, 17, 13 or any other practical number which is prime with respect to 24 and is less than 24.

The number of different paths which will be traced by the nozzle with a given pair of gears may be generally expressed by the formula

$$R = \frac{\text{L.C.M. (N) and (n)}}{n}$$

wherein R is the number of different paths, N

75

is the number of teeth on the larger gear and n is the number of teeth on the smaller gear. When the least common multiple of N and n is $N \times n$, as occurs when N and n are prime with respect to each other, the greatest number of diverse path units for a given pair of gears wherein the larger gear has N teeth, are attained. Thus, it will be seen that the number of different paths traced by the spray nozzle is primarily a function of the number of teeth on the larger gear, and this factor must be taken into consideration in constructing a nozzle for a given application. For general use, as for example in cleaning or coating drums, barrels, bottles, cans and the like having up to approximately 50 square feet of interior surfaces, the unit described above, i. e. a gear system wherein the larger gear is provided with 24 teeth and the smaller gear 23 teeth, has been found satisfactory. However, for certain applications, as for example in cleaning the interiors of drums or other large containers in which asphalt, resins or other analogous materials have been stored, it is advantageous to utilize a spray nozzle driven by a gear system in which the larger gear has a greater number of teeth, for example 48 teeth, and the smaller gear is provided with 47 teeth or another number which is prime with respect to 48. In this manner, 48 different paths will be traced by the impinging stream on the interior surfaces of the container.

In operation, the nozzle is inserted through the opening in the container and the container supported in such a manner that the nozzle is approximately in the center thereof, i. e. the nozzle head is as nearly as possible equidistant from all of the interior surfaces of the container. During cleaning operations, air inlet port 40 is plugged and a stream of cleaning fluid under pressure admitted through liquid inlet port 21. In many instances it has been found desirable to successively pass a number of cleaning agents through the nozzle during the cleaning operation. For example, in removing asphalt from containers, a particularly suitable cycle involves first passing heated hydrocarbon solvent through the nozzle during one or more complete cycles of revolutions of nozzle drive housing 7. This treatment is followed by a short period during which the liquid flow is interrupted and the container allowed to drain, or if desired, an air stream may be admitted through inlet port 21 to facilitate removal of the solvent. A heated caustic solution is then admitted through inlet port 21 during one or more cycles of rotations of nozzle drive housing 7, followed by a second draining period and then by a water flushing. Warm air may be introduced through the nozzle after the water rinse to facilitate drying of the interior surfaces of the container.

When used in coating applications, as for example in applying paint, lacquer, varnish, corrosion inhibition coatings and the like, air is admitted under pressure through air inlet port 40 and the liquid coating composition, also under pressure, through liquid inlet port 21. The liquid coating material is atomized in atomizing tip 35 and distributed evenly over the interior surfaces of the container. In such applications, the number of teeth on the nozzle driving gears may generally be less than when the nozzle is used primarily for cleaning purposes, since an atomized spray providing relatively great coverage is delivered from the nozzle rather than an impinging stream.

I claim as my invention:

1. In a spray nozzle assembly of the class described, the combination comprising a rotatable nozzle drive housing including a primary gear positioned therein, a secondary gear carried by and rotatable with respect to said nozzle drive housing engaging said primary gear, the longitudinal axis of said secondary gear being perpendicular to the longitudinal axes of said primary gear and said nozzle drive housing, a nozzle housing disposed externally to said nozzle drive housing mounted on said secondary gear and rotatable therewith, an atomizing nozzle mounted in said nozzle housing perpendicular to the axis of rotation of said nozzle housing, means for rotating said nozzle drive housing, means for supplying liquid under pressure to said atomizing nozzle and means for supplying air under pressure to said atomizing nozzle.

2. In a spray nozzle assembly of the class described, the combination comprising a rotatable nozzle drive housing including a primary gear positioned therein, a secondary gear carried by and rotatable with respect to said nozzle drive housing engaging said primary gear, the longitudinal axis of said secondary gear being perpendicular to the longitudinal axes of said primary gear and said nozzle drive housing, a nozzle housing disposed externally to said nozzle drive housing mounted on said secondary gear and rotatable therewith, an atomizing nozzle mounted in said nozzle housing perpendicular to the axis of rotation of said nozzle housing, means for supplying liquid under pressure to said atomizing nozzle, air conduit means in said nozzle drive housing, an annular air manifold disposed between said nozzle drive housing and said nozzle housing in flow communication with said air conduit means, air conduit means in said nozzle housing in flow communication between said air manifold and said atomizing nozzle, means for supplying air under pressure to said air conduit means in said nozzle drive housing and means for rotating said nozzle drive housing.

3. In a nozzle assembly of the class described, the combination comprising a rotatable nozzle drive housing, including a primary gear supported therein and non-rotatable with respect to said nozzle drive housing, primary conduit means extending through said primary gear, a secondary gear carried by and rotatable with respect to said nozzle drive housing engaging said primary gear, secondary conduit means extending through said secondary gear, the longitudinal axis of said secondary gear being perpendicular to the longitudinal axes of said primary gear and said nozzle drive housing, a nozzle housing disposed externally to said nozzle drive housing mounted on said secondary gear and rotatable therewith, an atomizing nozzle mounted in said nozzle housing perpendicular to the axis of rotation of said nozzle housing, flow communica-

tion means between said atomizing nozzle and said secondary conduit means, means for supplying liquid under pressure to said secondary conduit means through said primary conduit means, air conduit means in said nozzle drive housing, an annular air manifold in said nozzle drive housing between said nozzle housing and said nozzle drive housing in flow communication with said air conduit means, air conduit means in said nozzle housing in flow communication between said air manifold and said atomizing nozzle, means for supplying air under pressure to said air conduit means in said nozzle drive housing and means for rotating said nozzle drive housing.

4. In a nozzle assembly of the class described, the combination comprising a rotatable nozzle drive housing, a stationary nozzle assembly base including a conduit housing, conduit means extending through said conduit housing and into said nozzle drive housing, a primary gear in said nozzle drive housing supported by said conduit means in non-rotatable relationship with said conduit drive housing, primary conduit means in said primary gear in flow communication with said supporting conduit means, fluid sealing means between said supporting conduit means and said nozzle drive housing, a secondary gear carried by and rotatable with respect to said nozzle drive housing engaging said primary gear, secondary conduit means extending through said secondary gear, the longitudinal axis of said secondary gear being perpendicular to the longitudinal axes of said primary gear and said nozzle drive housing, a nozzle housing disposed externally to said nozzle drive housing mounted on said secondary gear and rotatable therewith, an atomizing nozzle mounted in said nozzle housing perpendicular to the axis of rotation of said nozzle housing, flow communication means between said atomizing nozzle and said secondary conduit means, flow communication means between said primary conduit means and said secondary conduit means, rotatable support housing means mounted on said conduit housing and supporting said nozzle drive housing, bearing means disposed between said conduit housing and said rotatable support housing and supporting said rotatable support housing on said conduit housing, means for rotating said support housing, air conduit means in said nozzle drive housing, an annular air manifold in said nozzle drive housing between said nozzle housing and said nozzle drive housing in flow communication with said air conduit means, air conduit means in said nozzle housing in flow communication between said air manifold and said atomizing nozzle, means for supplying air under pressure through said conduit housing and said rotatable support housing to said conduit means in said nozzle drive housing and air sealing means between said rotatable support housing and said conduit housing.

SIDNEY D. LAPHAM.
